Primary Examiner — Rosemary K Tarcza*Assistant Examiner* — Nathaniel D Buckner(74) *Attorney, Agent, or Firm* — Studebaker & Brackett PC(57) **CLAIM**

The ornamental design for a signal relay device, as shown and described.

DESCRIPTION

FIG. 1 is a perspective view of the front, left and top sides of a signal relay device showing our new design;

FIG. 2 is a perspective view of the rear, right, and bottom sides thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, showing a state of use; and,

FIG. 10 is another perspective view thereof, showing another state of use.

The broken lines shown represent unclaimed subject matter of signal relay device and form no part of the claimed design.
